DESIGN FOR A HEATER

Harold F. Hadley, Toledo, Ohio

Application December 29, 1934, Serial No. 54,640

Term of patent 7 years

To all whom it may concern:

Be it known that I, Harold F. Hadley, a citizen of the United States, and residing at Toledo, in the county of Lucas and State of Ohio, have invented a new, original, and ornamental Design for Heaters, of which the following is a specification, reference being had to the accompanying drawing, forming a part thereof.

In the drawing:

I claim:

The ornamental design for a heater substantially as shown.

Signed at Toledo, in the county of Lucas and State of Ohio, this 26th day of December, 1934.

HAROLD F. HADLEY.
